UNITED STATES PATENT OFFICE

114,119

DESIGN FOR AN EXHAUST EXTENSION

William H. Johnsen, Dallas, Tex.

Application January 26, 1939, Serial No. 82,625

Term of patent 7 years

To all whom it may concern:

Be it known that I, William H. Johnsen, a citizen of the United States of America and resident of the city of Dallas, county of Dallas, and State of Texas, have invented a new, original, and ornamental Design for an Exhaust Extension, of which the following is a specification, reference being had to the accompanying drawing, forming a part thereof.

Figure 1 is a side elevational view of the exhaust extension embodying my new design.

Fig. 2 is a top plan view thereof.

Fig. 3 is an end view as seen from the right of Fig. 1 or 2.

I claim:

The ornamental design for an exhaust extension, substantially as shown.

WILLIAM H. JOHNSEN.
